UNITED STATES PATENT OFFICE.

ELMER GEORGE GARTIN, OF CLAREMONT, NEW HAMPSHIRE, ASSIGNOR TO SULLIVAN MACHINERY COMPANY, A CORPORATION OF MASSACHUSETTS.

DRILLING APPARATUS.

Application filed December 30, 1919. Serial No. 348,464.

To all whom it may concern:

Be it known that I, ELMER GEORGE GARTIN, a citizen of the United States, residing at Claremont, in the county of Sullivan and 5 State of New Hampshire, have invented certain new and useful Improvements in Drilling Apparatus, of which the following is a full, clear, and exact specification.

My invention relates to drilling apparatus.

Its object is to provide a simplified and improved form of mounting for a rock drill. Another object of my invention is to provide an improved and simplified form of tool 15 mounting whereby the drill and its feed mechanism may be moved toward and from the face of the work. A further object of my invention is to provide an improved mounting in which the process of changing 20 steels is greatly simplified.

In the accompanying drawings I have shown, for purposes of illustration, one form which my invention may assume in practice.

25 In these drawings,—

Fig. 1 is a side elevation of a drill provided with a mounting embodying the illustrative form of my invention, parts being broken away to facilitate illustration.

30 Fig. 2 is a detail transverse section on the line 2—2 of Fig. 1.

In the drawings, a base 1 is provided, herein in the form of a trunnion adapted to be mounted upon any suitable support, and 35 on this base 1 is adjustably mounted, in an improved manner hereinafter described, a percussive motor 2 actuating a drill steel 3, the operation of the percussive motor being controlled by a usual manual throttle 40 valve 4 and its feed effected in a well known manner by the feed screw 5 and handle 6.

In my improved mounting, I have shown the percussive tool mounted upon a shell 7 of well known construction with which the 45 feed screw cooperates, but instead of mounting the shell directly on the base 1, I have rigidly secured in parallel relationship to the shell a bar 10. This bar is mounted in a guide 11 secured to the base member 1 and 50 may be suitably clamped in any desired position by the guide 11, which is, herein, of the split type, a clamp bolt 12 and nut 13 being shown herein as the clamp applying means. It will be obvious that by releasing 55 the nut 13, the entire shell may be moved

toward and from the work or swung in a lateral direction about the guide 11 or that it may be rigidly secured in any desired position with respect thereto.

The operation of my device in the changing of a drill steel is as follows: Let it be assumed that the usual limit of movement of the shell is materially less than the length of steel in use because of the depth of hole. It will then be obvious that, as the steel cannot be moved laterally at its rear end after disengagement from the chuck to clear the percussive motor when the latter is in retracted position, the tool cannot be withdrawn. With my improved device, all that is necessary to do, however, is, having released the tool from the chuck, to move it forward sufficiently to clear the front end of the chuck, and release the nut 13, move the percussive motor laterally about the guide 75 11 as a pivot and draw the steel straight out. A longer steel may then be inserted into the hole and the motor 2 swung back into position and the steel inserted again in the chuck.

It is thus seen that I have provided a mechanism whereby the position of the shell may be readily adjusted, and that by the adjustable mounting I have provided means for enabling the ready change of steels.

While I have in this application specifically described one form which my invention may assume in practice, it will be understood that this form of the same is shown for purposes of illustration and that the invention may be modified and embodied in other forms without departing from its spirit or the scope of the appended claims.

What I claim as new and desire to secure by Letters Patent is:

1. In combination with a rock drill, a shell upon which said rock drill is longitudinally adjustable, a base, and means for adjusting said shell longitudinally with respect to said base and about said base as an axis.

2. In combination with a rock drill having a mounting relative to which it is longitudinally adjustable, a second mounting for said first mentioned mounting comprising a guide, a bar attached to said first mentioned mounting extending through said guide, and means to adjust said first mentioned mounting longitudinally with respect to said guide or about said guide as an axis.

3. In combination with a rock drill, a

mounting comprising a base, a shell, said rock drill being mounted on and longitudinally adjustable with respect to said shell, a bar attached to said shell in parallel relationship thereto, a guide for said bar secured to said base, and means to clamp said bar in said guide.

4. In combination with a rock drill having a mounting relative to which it is longitudinally adjustable, a second mounting for said first mentioned mounting comprising a

guide, a bar attached to said first mentioned mounting extending through said guide, said guide and bar constituting means permitting adjustment of said first mentioned mounting longitudinally with respect to said guide or about the same as an axis, and means for retaining said first mentioned mounting in such adjusted position.

In testimony whereof I affix my signature.

ELMER GEORGE GARTIN.
